FOLDING COT AND CHAIR

Archibald J. Wright, Pelham Manor, N. Y.

Application November 18, 1940, Serial No. 366,088

4 Claims. (Cl. 155—45)

This invention relates to folding furniture, and more particularly to an article of furniture that can be folded to form either a chair or a cot.

Combinations of a folding cot and chair have been proposed heretofore, but such proposed articles have been very bulky and difficult to fold completely for transportation, or else they have not been as adaptable as would be desirable in converting them from a cot to a chair, or vice versa. In fact, some folding chairs and some combination chairs and cots are so complex that considerable difficulty is experienced by the ordinary person in folding or unfolding them.

With the large number of apartments and relatively small and compact living quarters in use at the present time, folding furniture is distinctly advantageous over bulky pieces of rigid furniture, and this is particularly true with respect to folding beds or cots which can be used in an emergency but which may not be needed for use as a bed or cot under ordinary circumstances.

One object of my invention is to provide a simplified combination folding chair and cot that is readily adjustable to form these different articles of furniture.

Another object is to provide a combination folding cot and chair that may be folded to form a cot or folded to form a chair with an independently adjustable back.

A further object is to provide a folding piece of furniture that may be folded compactly when not in use, or unfolded to form a cot or a chair with a tilted seat and an inclined adjustable back.

Other objects and advantages of this invention will be apparent from the description of a preferred embodiment thereof illustrated in the accompanying drawing, in which

Figure 1 is a plan view of a folded article of furniture arranged to form a cot.

Figure 2 is a side elevation of the article shown in Figure 1, illustrating in dot-dash lines the article as it may be folded to form a chair.

Figure 3 is a side elevation of the completely folded article ready for transportation or storage.

The folding article of furniture according to my invention may comprise a rectangular frame consisting of the end bars 10 and 11, the side frame sections 12, 13 rigidly connected to the end bar 10, the side frame sections 14, 15 pivotally connected to the sections 12, 13 respectively, the side frame sections 16, 17 pivotally connected to the sections 14, 15 respectively, and the side frame sections 18, 19 with one end pivotally connected to the frame sections 16, 17 and their other ends rigidly fixed to the end bar 11.

The pivotal joints connecting sections 12 to 14 and 13 to 15 preferably comprise the hinges 20 on the under side of these frame sections so that their ends abut each other to permit pivotal

movement of the sections in only a downward direction relative to the adjacent section, as viewed in Fig. 2. The connections between side frame sections 14 and 16 and between 15 and 17 may likewise consist of hinges 21 offset from the sections and disposed against the under sides of the sections. Hinges 21 may be connected by a reinforcing rod 22, although such a rod is not essential. Thus, the ends of sections 14 and 16 and of sections 15 and 17 abut each other in the position illustrated in Figs. 1 and 2, so that folding of these sections is only possible in one direction.

The adjacent ends of frame sections 16 and 18 and of frame sections 17 and 19 are preferably formed with inclined surfaces 23 and connected together for pivotal movement by the offset hinges 24. This permits raising of the frame sections 18 and 19 with respect to the frame sections 16 and 17 for a limited distance until the inclined surfaces 23 abut each other. If desired, a rod 25 may be used for reinforcement to connect the two hinges 24.

One end of the frame may be supported by the legs 26, 27 pivotally connected to the ends of the bar 10. Suitable rigid bracing links 28, 29 may be pivotally connected to the legs 26, 27 at points intermediate their ends, and carry inwardly projecting pins that fit into holes in the sides of frame sections 12 and 13. Thus, the links 28, 29 may be disengaged from the side frame sections 12, 13 when the article is to be folded.

A second pair of legs 30, 31 may be pivotally connected to the lower surfaces of the ends of side frame sections 16, 17 by means of the hinges 32. Hinges 32 are preferably disposed at one side of the upper ends of legs 30, 31 so that these legs may be folded up alongside the side frame sections 16, 17, but the legs are braced nevertheless by the upper ends striking the projecting hinges 24 (Fig. 1) when the legs are in the inclined position shown in Fig. 2. Suitable bracing links 33, 34 may be pivotally connected to the legs 30, 31 and carry inwardly projecting pins at their upper ends for insertion in the holes in the sides of frame sections 18, 19. For greater compactness when the article is completely folded, the links 33, 34 may be jointed at 33a, 34a and provided with the toes such as shown at 34b to hold the links rigid when they are straightened out as in Figs. 1 and 2.

The rectangular frame may have a covering consisting of the sections 35, 36, 37 and 38 of a suitable fabric such as a heavy canvas, joined together by the strips of elastic material 39, 40 and 41. The canvas sections and strips of elastic material, preferably a woven type of fabric containing elastic threads, may be stitched together to form one long strip of fabric attached to the frame in any suitable manner. For example, one

end of the canvas section 35 may be wrapped around the bar 10 and secured in place by stitching or other suitable means, and one end of the canvas section 38 may be wrapped around the bar 11 in a similar manner. The edges of each of the canvas sections along the side frame sections may be similarly wrapped around these frame pieces or secured thereto in some other manner. The ends of the elastic strips 39, 40 and 41 are preferably left free to permit easy folding of the article.

Various materials may be used for constructing this article of furniture. The bars 10 and 11 and the side frame sections may, for instance, be made of wood or metal, while the bracing links are preferably flat metal straps. The two pairs of legs may be made conveniently of either metal or wood.

To convert the article from a cot, as illustrated in Figs. 1 and 2, to a chair such as shown in Fig. 2 in dot and dash lines, it is simply necessary to disconnect the braces 33, 34 from the side frame sections 18, 19, raise this section to the desired inclination to form a back for the chair, and then insert the pins carried by braces 33, 34 in the appropriate holes in the side frame sections. The article may be used in this form as a lounging chair, or portable chaise longue. To provide front legs for the chair under the seat section between side frame sections 16, 17, the braces 28, 29 may be disconnected, the legs 26, 27 folded alongside frame sections 12, 13, and these legs and frame sections then folded downwardly through an angle of 180° until they lie against the frame sections 14, 15, respectively. When this entire folded unit is dropped down to a vertical position, the braces 28, 29 may be adjusted by inserting the pins carried by the free ends thereof in one set of the holes 42 in side frames 16, 17.

The elastic strips 39 and 40 stretch when these different sections of the frame are folded and thus prevent the sheet material covering from being pulled loose. It will be noted that the side frame sections 12, 13 are slightly shorter than the legs 26, 27, while the side frame sections 14, 15 are approximately the same length as the legs 26, 27. Therefore, when these parts are folded together and turned to the vertical, they provide front legs for the chair somewhat longer than the legs 26, 27 and tilt the seat of the chair. The amount of the tilt can be varied by the particular dimensions used for the different parts involved; in addition, the adjustment of the braces 28, 29 in different sets of the holes 42 can be used to provide different degrees of tilt for the chair seat.

A particular advantage of this article when used as a chair is the independent adjustability of the back and seat inclination to the most comfortable positions for any given individual.

This article may also be readily folded compactly for transportation or storage. After disengaging the braces 28, 29, the legs 26, 27, side frame sections 12, 13, 14 and 15 may be folded to a position alongside the side frame sections 16, 17. The braces 33, 34 may then be disengaged and the legs 30, 31 folded against the legs 26, 27 and the side frame sections 18, 19 folded against the other side frame sections. This leaves the article in a compact flat form that is easily carried by one person and that may be readily stored even in a small closet.

The terms and expressions which I have employed are used as terms of description and not

of limitation, and I have no intention, in the use of such terms and expressions, of excluding any equivalents of the features shown and described or portions thereof, but recognize that various modifications are possible within the scope of the invention claimed.

I claim:

1. A folding article of furniture comprising at least four rectangular frame sections pivotally connected together and arranged to be folded together and to be extended in an unfolded position with the sections all lying substantially in a common plane, a pair of legs pivotally connected to the free end of one of said sections, and a second pair of legs pivotally connected to another of said sections to support the other end of said frame, one of said sections being independently adjustable to form the back for a chair with a section adjacent thereto forming the seat for said chair, and the remainder of said sections being foldable with respect to said section and into a position adjacent each other so that said first mentioned legs extend downwardly from the front of said seat section and serve as front legs for the chair.

2. An article of furniture comprising a rectangular frame composed of a plurality of sections pivotally connected together, sections of sheet material attached to said frame sections to form a body supporting means, elastic strips connecting said sections of sheet material adjacent the pivotal connections of said frame sections to facilitate folding thereof, a pair of legs supporting one end of said frame, and a second pair of legs attached to said frame at a point spaced from the other end thereof, said frame sections being capable of extension to form a cot supported by said legs, and said frame sections being foldable with respect to each other to form a chair with said second pair of legs serving as the rear legs for said chair.

3. A folding article of furniture comprising a frame formed by at least four rectangular frame sections pivotally connected together so that they may be folded together or extended in a common plane, a pair of legs pivotally connected to one end of said frame, and a second pair of legs connected to the frame at points spaced from the other end for supporting the other end of said frame, said first mentioned legs and the frame sections adjacent thereto being foldable together to provide two angularly disposed units consisting of an inclined seat and front legs for a chair, said first mentioned legs serving as front legs for the chair, and the frame section adjacent said second pair of legs being adjustable to form the back for such a chair.

4. A combination folding chair and cot comprising a plurality of frame sections pivotally secured to each other so that they may be folded compactly together for storage or extended in a common plane, a section at one end of the frame being pivotally adjustable to form the back of a chair, the frame section adjacent thereto forming a seat for such chair, a pair of legs attached to the frame at the junction of said back and seat sections, the others of said frame sections being foldable together and into a position below said seat section, and another pair of legs pivotally secured to the free end of one of said other frame sections to support one end of the frame in unfolded position and to serve as the front legs of the chair when said other sections are folded together.

ARCHIBALD J. WRIGHT,
